VENTILATOR FOR BUILDINGS.

1,074,143.

Specification of Letters Patent. Patented Sept. 30, 1913.

Application filed June 10, 1912. Serial No. 702,913.

To all whom it may concern:

Be it known that we, THOMAS E. VAUGHN and JOHN H. BRUNINGA, citizens of the United States, and residing at Chicago and St. Louis, respectively, in the States of Illinois and Missouri, respectively, have invented certain new and useful Improvements in Ventilators for Buildings, of which the following is a specification.

This invention relates to ventilators for buildings, chimneys, and the like, and more particularly to ventilators of the ejector type.

One of the objects of this invention is to provide a ventilator which not only forms an outlet opening for the air from a building or the like, but which is so constructed that outside air currents striking the same will produce by an induced action a strong exhaust of the air from the interior of the building.

Another object is to provide a ventilator which will be simple in construction, cheap to manufacture, will require a minimum of seams, and which is so arranged that one part will be nested within the other so that the whole will form a strong and rigid construction.

Further objects will appear from the detailed description taken in connection with the accompanying drawings in which:

Figure 1 is a side elevation of a ventilator embodying this invention, Fig. 2 is a section on the line 2—2 Fig. 1, Fig. 3 is a view of the ventilator taken from below, Fig. 4 is a perspective view of the self-contained member forming one of the elements of the ventilator. Fig. 5 is an elevation of a ventilator showing another embodiment of this invention, and Fig. 6 is a section on the line 6—6 Fig. 5.

Referring to the accompanying drawings, and more particularly to Figs. 1-4 inclusive, 10 designates an eduction pipe which is arranged to be attached to a building, chimney, or the like in any suitable manner so as to form an exhaust therefor. An intermediate cone-shaped member 11 is corrugated or shaped to form a series of lobes comprising outer folds or flutes 12 and inner folds or flutes 13. This member is mounted upon the eduction pipe and is secured thereto by rivets passing through the inner folds 13 and the eduction pipe. A

plain cone or casing 14 is mounted upon the intermediate member and is secured thereto by rivets extending through the cone and through the outer folds 12. The intermediate member forms with the eduction pipe and cone 14 a series of vertical induction passages open at the lower end and discharging at the upper end inside of the cone 14. The upper end of the intermediate member extends substantially flush with the upper end of the eduction pipe, and the eduction pipe is cut away at 15 and opposite the outer folds 12 as shown in the drawing. The intermediate member extends a short distance below the cone 14, and the extension of the inner folds 13 is greater than that of the outer folds 12. This construction provides deflecting surfaces for deflecting the outside cross currents upwardly.

A cone-shaped cap 16 is supported upon the cone 14 by means of straps 17 riveted to the cap and to the cone. The inside of the cap has riveted thereto a downwardly extending conical member 18, and the outside rim of the cap is provided with a downwardly extending flange 19.

The intermediate member forms with the eduction pipe and cone 14 a series of vertically extending induction passages. As the outside air currents strike the sides of the ventilator, these air currents will be deflected upwardly and will pass through the induction passages and cause an inducted draft through the eduction pipe 10. As the air from the eduction pipe and from the passage passes upwardly, it will strike the conical member 18 and will be deflected outwardly so as to pass out through the space between the cone 14 and the cap 16. The conical member 18 will thus deflect the exhausted air outwardly and out of the ventilator, causing a smooth exhaust action and preventing the formation of eddy currents which would be caused if the member 18 was absent. The area of the outlet space between the cap 16 and the cone 14 is as great or a little greater than the area of the outlet of the cone 14, but the cap is placed close enough to the upper end of the cone 14 so that the outside cross currents will not blow down the ventilator. The bottom of the cone is also placed low enough, and the diameter of the outside rim

is made large enough and extends down low enough so that the rain cannot enter the ventilator directly and so that the wind will not blow in the water which drips down 5 from the edge of the cap.

Figs. 5 and 6 illustrate another form of ventilator. In this construction the intermediate member is formed with angular folds or lobes so as to form inner and outer surfaces 21 and 22 conforming to the surfaces of the eduction pipe 20 and the cone 23 respectively. The eduction pipe is not cut away in this case as in the other construction, but its upper end stops a short 10 distance below the upper end of the intermediate member. The lower inner ends of the folds extend some distance below the lower ends of the outer folds as in the construction shown in Figs. 1 to 4 inclusive, 15 and the outer folds also extend a short distance below the lower end of the outer cone. The cone 24 provided with the inner conical member 25 is mounted upon the body of the ventilator by means of straps 26, but the 20 rivets extending through the strap pass in this case through both the intermediate member and the cone 23. The operation of this device is substantially the same as that described in Figs. 1 to 4 inclusive. Due to 25 the angular construction, the intermediate member can be formed easier than that shown in Figs. 1 to 4 inclusive, and the parts will be more firmly nested when assembled.

30 35 The lobes where they engage the casing and the pipe extend for some distance circumferentially therealong. This will cause the spans between the lobes to be decreased, and also results in a better and more uniform 40 distribution of the entering air currents.

It will be noted that the body of the ventilator consists of three parts, an induction pipe, an intermediate member, and an outer 45 side cone. The intermediate member is so constructed as to form a unitary, substantially continuous and self-contained structure. The elements of the ventilator are nested one within the other so that one will 50 support the other; the number of seams and joints can therefore be reduced to a minimum which not only results in a minimum of labor and expense but also reduces the number of seams and rivet joints which are liable to rust out. In the construction shown 55 in Figs. 5 and 6, the cap itself is supported by both the outer cone and the intermediate member. The entire ventilator is preferably constructed of sheet metal, and the in-

termediate member can then be formed of 60 a single sheet folded or fluted to shape in any suitable manner. In the constriction shown in Figs. 5 and 6 this folding may be readily performed with an ordinary 65 brake.

It is obvious that various changes may be made in the details of construction without departing from this invention, and it is therefore to be understood that this invention is not to be limited to the specific construction shown and described.

We claim—

1. A ventilator comprising an eduction pipe, a casing surrounding said pipe, and means for supporting said casing in spaced 75 relation with respect to said pipe comprising a plurality of lobes extending along said pipe and engaging both said pipe and said casing, said lobes being connected to form a substantially continuous element surrounding 80 said pipe and inside of said casing, whereby a plurality of passages are formed inside of said casing and extending along said pipe.

2. A ventilator comprising an eduction 85 pipe, a casing surrounding said pipe, and means for supporting said casing in spaced 90 relation with respect to said pipe comprising a plurality of lobes extending along said pipe and engaging both said pipe and said casing, said lobes being formed to extend circumferentially along and in engagement with said casing, said lobes being connected to form a substantially continuous element surrounding 95 said pipe and inside of said casing, whereby a plurality of passages are formed inside of said casing and extending along said pipe.

3. A ventilator comprising an eduction pipe, a casing surrounding said pipe, means 100 for supporting said casing in spaced relation with respect to said pipe comprising a plurality of lobes extending along said pipe and engaging both said pipe and said casing, said lobes being connected to form a 105 substantially continuous element surrounding said pipe and inside of said casing, whereby a plurality of passages are formed inside of said casing and extending along said pipe, and a cap supported above said 110 pipe and by said casing and said lobes.

In testimony whereof we affix our signatures in presence of two witnesses.

THOMAS E. VAUGHN.
JOHN H. BRUNINGA.
